(57) **CLAIM**

The ornamental design for a bilateral mechanism, as shown and described.

DESCRIPTION

FIG. 1 is an isometric view of the front of the bilateral mechanism, which embodies my design;

FIG. 2 is a front view of the bilateral mechanism;

FIG. 3 is an rear view of the bilateral mechanism;

FIG. 4 is a top plane view of the bilateral mechanism;

FIG. 5 is a bottom plane view of the bilateral mechanism;

FIG. 6 is a left side of view of the bilateral mechanism;

FIG. 7 is a right side of view of the bilateral mechanism; and,

FIG. 8 is an exploded of view of the bilateral mechanism.
